Term of patent 14 years

Int. Cl. D8—05; D12—13

U.S. Cl. D35—2 B

FIG. 3

FIG. 1 is a perspective view of the auger, the auger having two flights, each with two blades, at each end for moving materials toward its longitudinal center; a perspective view of the auger from the other end being substantially a mirror image;

FIG. 2 is an end view of FIG. 1; and

FIG. 3 is a perspective view as seen from the right and bottom of FIG. 1, a portion being shown for clarity.

I claim:

The ornamental design for an auger usable to move materials such as snow and the like, as shown and described.
